US0D1112603S

(12) **United States Design Patent** (10) **Patent No.:** **US D1,112,603 S**
(45) **Date of Patent:** **** Feb. 10, 2026**

(54) **WATER FILTER**

(71) Applicant: **Rama Pure Water Private Limited,**

Chennai-Tamil Nadu (IN)

(72) Inventor: **Rajesh Ramanathan Balachandran,**
Chennai (IN)

(73) Assignee: **Rama Pure Water Private Limited,**
Chennai Tamil Nadu (IN)

(**) Term: **15 Years**

(21) Appl. No.: **29/918,528**

(22) Filed: **Nov. 28, 2023**

(30) **Foreign Application Priority Data**

Aug. 23, 2023 (IN) 393464-001

(51) **LOC (15) Cl.** **23-01**

(57) **CLAIM**

The ornamental design for a water filter as shown and described.

DESCRIPTION

FIG. 1 is a first perspective view of a water filter showing the design;

FIG. 2 is a second perspective view thereof;

FIG. 3 is a third perspective view thereof;

FIG. 4 is a first side view thereof;

FIG. 5 is a second side view thereof;

FIG. 6 is a top view thereof; and,

FIG. 7 is a bottom view thereof.

Broken lines shown in the drawings illustrate portions of the article and form no part of the claimed design.

1 Claim, 7 Drawing Sheets
